UNITED STATES PATENT OFFICE.

GEORGE LENOX CURTIS, OF NEW YORK, N. Y., ASSIGNOR TO EDWARD C. GOODWIN, OF WORCESTER, MASSACHUSETTS.

OZONE-GENERATOR.

SPECIFICATION forming part of Letters Patent No. 727,101, dated May 5, 1903.

Application filed January 17, 1903. Serial No. 139,409. (No model.)

To all whom it may concern:

Be it known that I, GEORGE LENOX CURTIS, a citizen of the United States, residing at New York, in the county of New York and State of New York, have invented certain new and useful Improvements in Ozone-Generating Apparatus; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in ozone-generating apparatus; and my aim is to produce a novel device simple in construction and portable and designed for use for therapeutic and various 20 other purposes and adapted to transmit the ozone generated either by direct contact of the apparatus with a person or through the medium of the atmosphere intervening between the apparatus and the user.

25 More specifically, the present invention consists in the provision of an open-ended cylinder of glass or other suitable material, which may or may not be provided with a metallic lining provided for the purpose of distributing 30 the electrical energy over a considerable surface of the cylinder, and in the provision of an exhausted tube which is supported within the cylinder by suitable insulating means and one end of which tube is provided with 35 a cap to which a high-tension electric current is adapted to be connected, the inner surface of the exhausted tube being provided with a metallic lining electrically connected with the cap to which the current is applied.

40 Another feature of the invention consists of the provision, in connection with the cylindrical shell and the exhausted tube, of an exhausted Geissler tube which is connected by a suitable means to said cylindrical shell and 45 having, preferably, a metallic wire extending from the interior of the shell into the Geissler tube, thereby providing means whereby the ozone which is generated as it passes through the apparatus may be conveyed by induction 50 from the shell to the handle and given off either by a direct contact with the handle or at

the open ends of the shell, thus affording convenient means for allowing the ozone to be breathed by bringing the flaring end of the shell adjacent to the head of a patient or by 55 direct contact with the handle in which a deep-violet light is produced when the apparatus is connected up with a high-tension coil.

The invention consists, further, in various details of construction and combinations and 60 adaptations of parts, which will be herein-after fully described and then specifically defined in the appended claims.

My invention is illustrated in the accompanying drawings, which, with the letters of reference marked thereon, form a part of this application, and in which drawings—

Figure 1 is a side elevation of my improved ozone-generating apparatus. Fig. 2 is a central sectional view through the cylinder, the exhausted tube mounted therein, and the Geissler tube connected with the cylinder. Fig. 3 is a sectional view through the exhausted tube adapted to be held within the shell. Fig. 4 is a perspective view showing a plurality of tubes mounted within the cylindrical shell, some of said tubes being shown as closed and designed to be exhausted tubes, while others are designed to be open at one end.

Reference now being had to the details of the drawings by letter, A designates an open-ended cylindrical shell of the ozone-generator and may be made either of glass or other suitable material. One end of said shell, as A', is slightly flaring, adapting the same to be 85 held adjacent to the breathing apparatus of a person, whereby the ozone may be taken through the lungs for the purpose of having a beneficial influence upon the blood as it circulates through the lungs. Said shell is 90 preferably provided with a metallic lining B upon its inner circumference, or, if desired, said lining may be dispensed with. This lining covers considerable of the inner circumference of the shell, and portions of said lining 95 extend into the laterally-projecting tubular extension B' of the shell. Mounted within the cylindrical shell is preferably an exhausted tube C, having integral spurs C' projecting radially from the circumference thereof at locations adjacent to the ends of the tube, and D designates rubber shoes, which

are fitted over said lugs and are adapted to be held yieldingly against the inner circumference of the cylindrical shell at locations preferably beyond the ends of the metallic lining to the shell. Said insulating shoes D bear against the inner circumference of the shell with sufficient pressure to support the tube centrally within the shell, the friction between said shoes and the circumference of the shell being such as to allow the tube to be easily removed from the shell when desired. A portion of the inner circumference of said tube C is provided with a metallic lining E, and it will be observed from Figs. 2 and 3 of the drawings that a metallic wire F is diametrically disposed within the tube C, with its ends embedded in the lining to said tube, and a wire G is connected at one end to the cross-wire F, and its other end is connected to the cap H, to which a wire K, adapted for connection with a high-tension current, is attached. Said cap is fitted over an insulating plug L, seated in the contracted end of the tube C.

25 Fitted over the tubular extension B of the shell is a thimble N, made, preferably, of metal, the inner circumference of which is threaded, as at N', and adapted to receive a threaded thimble M, which is fitted over a filling O, which extends into the contracted end of the exhausted tube Q, forming the handle of the apparatus, which may be a Geissler or any other suitable tube. A wire R passes through an open-ended tubing R', one end of which is seated in said filling O in the contracted portion of the tube Q and its other end passing through the filling, and a plug J extends centrally through the tubular projection B, with its inner end within the cylindrical shell.

40 Referring to Fig. 4 of the drawings, I have shown instead of a single exhausted tube within the cylindrical shell a plurality of tubes, which are supported in insulating members T within the shell, and a portion of said tubes (designated by letters W) are shown as closed or exhausted tubes, while tubes W' are shown with open ends. The opposite ends of said tubes are provided with caps P, which are connected, by means of the wires P', with the cap H, whereby a high-tension current may be connected to the various tubes.

45 The manner of generating ozone by the apparatus comprising my invention consists in introducing electricity of high tension from any suitable source of supply to the metallic cap at the end of the inner tube or tubes. The electricity being conducted through the central wire in the inner tube to the coating 50 about the circumference of the latter will cause the outer shell and the handle to become charged by induction, and the ozone will be liberated from the oxygen in the air, due to the disruption of the air caused by 55 electrical discharging, and deep-violet light-waves will be generated in the shell. The electrical charge induced on the extremity R

on the handle O induces through the rarefied space a charge of opposite polarity, which in turn induces a charge of opposite polarity on the opposite end of the tube. There is thus induced upon the surface of the hand of the person holding the handle a charge of high potential, which charge is conducted through the hand and body of the person to the earth. 75 By holding the apparatus adjacent to a person's nose the odor of the ozone may be readily detected, and treatment may be had by direct contact with the handle of the generator. Owing to the utilization of a high-tension current, it has been demonstrated that the same deep-violet light may be induced within an exhausted tube when held some distance from the apparatus, thus proving that the effect of the ozone may be experienced without direct contact with the apparatus, the surrounding atmosphere serving as a medium for conducting the same from the device to the body of a person, it being understood that my apparatus is unipolar, the body of a person and the medium of the atmosphere serving as the opposite pole.

50 While I have shown in the present invention a metallic lining for the inner tube and shell and the inner tube preferably exhausted or closed, it will be understood that the lining, if desired, may be dispensed with, and I may make other alterations in the detailed construction of the apparatus without departing from the spirit of the invention. 100

Having thus fully described my invention, what I claim as new, and desire to secure by Letters Patent, is—

1. An ozone-generator comprising an open-ended shell, an exhausted tube mounted within and insulated from said shell, a metallic cap on one end of said tube, electrical connection with said cap, and a handle fastened to said shell, as set forth. 105

2. An ozone-generator comprising an open-ended shell, an exhausted tube mounted within and insulated from said shell, electrical connection with one end of the tube, and an exhausted tubular handle to the shell, as set forth. 110

115 3. An ozone-generator comprising an open-ended shell, an exhausted tube mounted within and insulated from said shell, a lining over a portion of the circumference of said tube, a cap over one end of the tube, electrical connections between the same and said lining, and an exhausted tubular handle fastened to said shell, as set forth.

4. An ozone-generator comprising an open-ended shell, an exhausted tube mounted within and insulated from said shell, a metallic lining over a portion of the surface of said exhausted tube, a metallic cross-piece mounted within said tube, a cap over one end of the tube adapted for connection with a high-tension current, metallic connections between said cap and lining, and an exhausted tubular handle connected to said shell, as set forth. 120 125 130

5. An ozone-generating apparatus compris-

- ing a cylindrical open-ended shell, a metallic lining over a portion of the inner circumference thereof, an exhausted tube mounted in and insulated from said shell, a lining to the 5 exhausted tube, a cap over the contracted end of the tube, metallic connections between said cap and the lining of the exhausted tube, and an exhausted tubular handle connected to the shell, as set forth.
- 10 6. An ozone-generating apparatus comprising an open-ended shell, an exhausted tube having integral lugs projecting therefrom, insulating-shoes mounted over said lugs and adapted to frictionally engage the inner 15 circumference of the shell and support said tube, a cap over one end of the exhausted tube adapted for connection with a high-tension current, and an exhausted tubular handle to the shell, as set forth.
- 20 7. An ozone-generating apparatus comprising an open-ended shell, a metallic lining over a portion of its surface, an exhausted tubular handle to said shell, an exhausted tube within the shell, flexible insulating-shoes carried by 25 said tube and adapted to frictionally engage the inner circumference of the shell, a metallic cap over the contracted end of the tube, a metallic lining to the exhausted tube, and metallic connections between said cap and 30 lining to the tube, as set forth.
8. An ozone-generating apparatus comprising

ing an open-ended shell, an exhausted tube mounted within the same and insulated therefrom, a cap over one end of said tube adapted for connection with a high-tension 35 current, a tubular extension on said shell, and an exhausted tube fitted thereto, as set forth.

9. An ozone-generating apparatus comprising an open-ended shell, a tube with contracted end mounted within the same and insulated therefrom, a lining to said tube, a cap over the contracted end of the tube and adapted for connection with a high-tension 40 current, a thimble fitted over a tubular projection on the shell, and an exhausted tube 45 fitted to said thimble, as set forth.

10. An ozone-generating apparatus comprising an open-ended shell, an exhausted tube removably mounted within said shell and insulated therefrom, a metallic lining to said 50 tube, a cap over one end thereof, and metallic connections between the same and said lining, a thimble fitted over a tubular extension of the shell, an exhausted tube, a filling at one end thereof, and a threaded thimble 55 fitted to said tubular extension, as set forth.

In testimony whereof I hereunto affix my signature in the presence of two witnesses.

GEORGE LENOX CURTIS.
